AUTOGRAPHIC REGISTER

Louis Jensen, Chicago, Ill., assignor to United
Autographic Register Co., a corporation of
Illinois

Application July 16, 1932, Serial No. 622,929

11 Claims. (Cl. 282—12)

The present invention pertains to a simple form of autographic register, adapted to be carried in the hand and to serve as a substitute for sales books, or sales pads.

5 The invention provides a simple, practicable device of the character indicated which enables continuous-form stationery to be employed in a hand-carried device.

The invention constitutes a modification of and 10 improvement upon the invention described in Jensen application Ser. No. 569,338, filed October 16, 1931.

Referring to the accompanying drawing, which illustrates a preferred embodiment:

15 Fig. 1 is a perspective view, slightly broken, of a register embodying the invention; Fig. 2, a vertical longitudinal sectional view of the same, the dotted lines showing the rear end-closure in open position; Fig. 3, a transverse sectional view taken 20 as indicated at line 3 of Fig. 2; Fig. 4, a fragmentary view in the nature of a section taken as indicated at the line 4 of Fig. 3; Fig. 5, a broken plan view illustrating a slight modification of the carbon-holder; Fig. 6, a transverse section taken 25 as indicated at line 6 of Fig. 5; and Fig. 7, a broken perspective view similar to Fig. 1, showing a slight modification.

Referring to the embodiment shown in Figs. 1-4, A designates a shallow, elongated casing, 30 adapted to serve as a supply-compartment containing a zig-zag folded packet of continuous-form stationery; B, a platen forming a top for said compartment; and C, a skeleton-cover which preferably is detachably connected with the casing by means of snap-buttons.

The casing A is shown as comprising a bottom wall 1, lateral walls 2, and a front end-wall 3. Preferably, the bottom wall comprises a stationary main section 1^a and a pivoted section 1^b whose front end is connected by a hinge 4 to the rear end of the stationary member 1^a.

In the form illustrated, the pivoted bottom section 1^b is formed integrally with an end-wall 1^c which embraces the rear edges of the side-walls 2 and is equipped with a catch-flange 1^d which engages notches 5 with which the rear upper corners of the side-walls 2 are provided.

The bottom-wall of the casing preferably is provided with buttons or hollow bosses, 6, which 50 may be formed by stamping the metal of the bottom downwardly. Preferably, two of these bosses are placed near the front end of the bottom, and two of them are associated with the pivoted bottom-section 1^b.

55 The platen B is shown as consisting of a thin

sheet of metal 7 which forms the top wall of the compartment, and flanges 7^a which embrace the upper portions of the side-walls 2. The rear end of the platen has a depending flange 7^b which is spaced some distance in front of the rear end wall 1^c.

The upper edges of the side walls 2 of the casing are provided with clenching-lugs indicated at 2^a, which extend through slots in the plate 7 and serve to secure the platen in position. Also, the side walls 2 have forward extensions 2^b which project in front of the end-wall 3 and are provided with inturned flanges 2^c. The platen has a forward extension 7^c which rests upon the flanges 2^c and is secured thereto by means of studs 8 15 which serve also as stop-lugs, or register-pins. The members 8 are shown as flat pieces of metal which have reduced shanks which extend through slots in the extension 7^c and through the inturned flanges 2^c, these reduced shanks being riveted at 20 their lower ends, as indicated at 8^a.

Also, the platen B is provided just back of the end-wall 3 with a transverse depression 7^d, the purpose of which will be explained later. The lateral flanges 7^a of the platen are provided with 25 outwardly struck hollow bosses 7^e, which constitute the inner members of snap-buttons adapted to secure the skeleton cover C in position.

Just back of the platen and below the left thereof, a guide-roll 9 is journaled in the rearward extensions of the side walls 2 of the casing. An abutment 10 is associated with a guide-roll being preferably disposed below and slightly in front of the guide-roll. In the form shown, the abutment comprises an angular member having 35 a horizontal flange 10^a secured to the pivoted bottom section 1^b, having a vertical member 10^b which is equipped with spring-fingers 10^c adapted to coact with the guide 9 and apply light tension to the stationery.

D designates a packet of zig-zag folded stationery within the supply-compartment, from which strips D' are led rearwardly about the guide 9, and thence forwardly over the platen B. A carbon-strip 11 is interposed between the paper-web. In the illustration given, the rear margin of the carbon strip is secured within the U-fold of a transverse flexible strip 11^a, which may be of celluloid, if desired.

50 The side flanges 2 of the casing are shown provided at their upper edges with notches 12; and the carbon-holder 11^a is shown engaging the front set of notches. After the carbon has been used for a time the holder may be shifted to the 55

rear set of notches to enable the portions of the carbon which is in active use to be renewed.

The skeleton-cover C is shown as comprising a metal plate 13 which is cut away, as indicated at 5 13^a, to expose the stationery D'. This plate is provided with corresponding lateral flanges 13^b and a depending rear flange 13^c, which is equipped centrally with a finger-grip 13^d. The flanges 13^b embrace the flanges of the platen and are 10 equipped with outwardly struck bosses 13^e, adapted to act as snap-buttons and engage the bosses 7^e with which the flanges of the platen are equipped. The construction of the skeleton cover C is such that the rear flange 13^c may be 15 brought into engagement with the rear end wall 1^c, and the cover may then be pressed downward into position, in which action, the buttons 13^e are snapped into engagement with the buttons 7^e.

The cover C has at its front end a transversely 20 extending member 13^f, which is equipped at its lower side with a transverse elongated boss 13^g, which is adapted to depress the paper webs D', near their front edges, into the depression 7^d, the result being to cause the front ends of the paper webs to be bent upwardly as indicated at 14 in 25 Figs. 1 and 2. This enables the front edges of the strips to be grasped by the thumb and fingers, when it is desired to draw the strips forwardly. This expedient renders unnecessary the notching 30 of the platen-extension, or ledge, 7^c—a feature which is of advantage in tearing off the strips. Preferably, the depending projection 13^g is larger, or deeper, at its center portion so that there is a 35 tendency to cause the intermediate portions of the strips of paper to project upwardly as appears in Fig. 1. If desired, an upwardly projecting boss or lip 7^f may be provided in front on the depression 7^d, as illustrated in the modification shown in Fig. 7, which serves to further assure the upward bending of the front edges of the strips.

It is preferred to provide, near the front end 40 of the platen, lateral guides 15 adapted to engage the edges of the paper-strips. In the illustrations shown in Figs. 3 and 4, these members are provided by lugs which extend upwardly from the upper edges of the side walls 2 of the casing through slots in the platen, the upper portions of the members being bent inwardly to provide projections 15^a adapted to overlie the margins of the 45 strips. The lateral guides 15 are closely associated with the stops 8. The strips of stationery are provided at the form-lengths with transverse lines of weakening, and with V-shaped notches at the ends of these lines of weakening. In Fig. 55 1, the used forms have been detached, so that the front ends of the strips correspond with the lines of weakening, and only the oblique faces 16 of the rear portions of the V-shaped notches are shown. The pins or studs 8 are located in oblique 60 planes and engage the oblique faces 16 of the notches.

In the modification shown in Figs. 5 and 6, the casing is designated A', and the platen is designated B'. The construction is the same as the 65 previously described construction, except that the carbon paper, designated 17, consists of a plain strip of paper having its rear end portion looped or folded and engaged by a thin retainer strip 70 17^a having in one end a perforation which engages a loop, or curved wire, 17^b, carried by one of the side-walls 2. The other end of the strip or flexible bar 17^a engages a slot 17^c in the other side wall of the casing. When desired, the free end of the 75 member 17^a may be disengaged, and the member

may be swung out of the way, the pivoted end sliding on the member 17^b.

The improved register may be formed mainly 5 from sheet aluminum.

Preferably, it is of such size that the device may 10 rest in the palm of the left hand and be embraced by the thumb and fingers, very much as a narrow writing tablet may be held in the hand. The device may be conveniently carried in the 15 pocket, and may be employed in freight yards, 10 and in shipping rooms where often it is desirable for the person making out shipping receipts, way bills, or the like, to move about and always have ready at hand a duplicating machine of this character. 15

The foregoing detailed description has been given for clearness of understanding only, and no unnecessary limitations should be understood therefrom, but the appended claims should be construed as broadly as permissible, in view of 20 the prior art.

What I regard as new, and desire to secure by Letters Patent, is:

1. A device of the character set forth, comprising 25 a casing adapted to contain continuous-form stationery, said casing equipped with a platen having a recess near its front end, and a skeleton cover adapted to overlie stationery strips extending across the platen, said cover having its front portion equipped with a projection coacting with 30 said recess and adapted to bend the front margins of the strips upwardly.

2. A register of the character set forth comprising: an elongated casing adapted to contain 35 zig-zag folded continuous-stationery, said casing being equipped with a top constituting a platen having a recess near its front end, said platen having a forward extension forming a ledge; register-pins carried by said ledge; and a skeleton cover adapted to overlie stationery strips 40 extending across said platen, said cover having its front end portion equipped with a depending projection adapted to bend the strips into said recess and thereby turn the front margins of the 45 strips upwardly.

3. A register of the character set forth comprising: an elongated shallow compartment 50 adapted to contain a zig-zag folded packet of continuous-form stationery; a platen forming a top for said compartment and having the front extension forming a ledge, said platen having a transverse recess back of said ledge; a guide near the rear end of the platen about which strips may be led from the compartment and over the platen; and a skeleton-cover having a front cross-member equipped with a rib adapted to depress the strips of stationery into the upper portion of said recess and cause the front ends of the strips to be bent upwardly. 55

4. A register of the character set forth comprising a shallow, elongated casing equipped with a top member constituting a platen, the bottom wall of said casing having a pivoted extension carrying an end wall for the casing, a transverse guide near the rear end of said platen, an abutment in said casing spaced from said rear end wall and disposed beneath said guide; and a skeleton cover over said platen and having a rear end portion embracing the rear portion of the casing including the upper portion of the rear end wall thereof. 60

5. An autographic register comprising a shallow, elongated compartment adapted to contain a packet of zig-zag folded stationery, said compartment having a rear end closure pivotally com- 75

- nected with the bottom of the compartment; a platen forming a top wall for said compartment and a guide roll near the rear end of said platen and a coating strip-tensioning device spaced 5 from the guide-roll; and a skeleton cover adapted to overlie stationery strips passing from said guide roll across said platen, said cover having flanges embracing the upper rear portion of said compartment including said rear end-closure.
- 10 6. An autographic register comprising a shallow elongated compartment having a bottom wall equipped with a pivoted extension carrying a rear end wall for the compartment; a platen forming a top wall for said compartment; a guide-roll disposed near the rear end of said platen; an abutment carried by the pivoted member and yieldingly co-acting with said guide-roll to frictionally engage strips led from said compartment; and a skeleton cover having flanges embracing 15 the upper portion of the compartment and rear end closure.
- 15 7. An autographic register comprising an elongated shallow compartment equipped with a top wall constituting a platen having a recess near its front end, said platen having a forward 20 extension forming a ledge; flat register-pins carried by said ledge and adapted to engage V-shaped notches at the lateral edges of stationery-strips; a guide near the rear end of the platen 25 over which stationery-strips may be drawn across the platen; and a skeleton-cover embracing the upper portion of the compartment and equipped at its front end with a cross-member having a depending projection adapted to bend the stationery strips into said recesses and thereby turn 30 the front end portions upwardly.
- 20 8. An autographic register comprising a casing provided at its upper portion with a platen and beneath said platen with an elongated supply-compartment adapted to contain zig-zag folded 35
- 25 continuous stationery, a transverse guide in said casing near the rear end of said platen about which stationery may be drawn from said supply-compartment on to said platen, a pivotally mounted angular member having a member constituting a portion of the bottom of the casing and having a member forming an end wall for the casing, and an abutment member carried by 40 said angular member and spaced from the member which forms said end wall and having its upper portion forming a guide for the stationery disposed in front of said first-mentioned guide.
- 30 9. A device as specified in claim 1, in which the platen is further provided with a short upwardly extending boss positioned in front of said recess so as to further assist in bending the strips upwardly.
- 35 10. An autographic register comprising a compartment for continuous-form stationery, a platen equipped on its upper surface near its front end with a projection, and a guide-member 45 overlying the strips back of said projection adapted to coact with said projection to bend the front ends of stationery-strips upwardly.
- 40 11. An autographic register comprising a shallow elongated compartment having side walls provided near their upper rear portions with sets of notches; a top for said compartment forming a platen; a transverse guide near the rear of 50 said platen over which strips may be drawn from said compartment to said platen; a skeleton cover adapted to fit over the platen and form a closure for said notches; and a carbon holder adapted to engage either set of said notches, the thickness 55 of said holder being substantially less than the depth of the notches so that the holder may float between said strips of stationery when said cover is in position.

LOUIS JENSEN. 40
